WEAR COMPENSATING DEVICE FOR WASHING MACHINE CYLINDER DOORS

William Strobridge, Syracuse, N. Y., assignor to
 United States Hoffman Machinery Corporation,
 New York, N. Y., a corporation of Delaware

Application November 14, 1935, Serial No. 49,670

2 Claims. (Cl. 220—32)

This invention relates to wear compensating devices for washing machine cylinder doors of the type illustrated in United States Patent No. 1,984,931.

An object of the invention is to ensure the tight closing of the doors of washing machine cylinders, both initially and after wear takes place, by providing simple, efficient and durable means for accomplishing this purpose.

The invention accordingly consists in the features of construction, combinations of elements, and arrangements of parts as will be exemplified in the structure to be hereinafter described and the scope of the application of which will be indicated in the following claims.

In the accompanying drawings, in which is shown one of the various possible embodiments of the invention,

Figure 1 is a front elevation of a fragment of a cylinder for a washing machine showing a door hinge and latch assembly embodying the present invention;

Fig. 2 is a side elevation of the assembly shown in Fig. 1;

Fig. 3 is a section on line 3—3 of Fig. 1;
 Fig. 4 is an elevation of one of the stationary hinge members for the lower door, showing the lower end of one of the hinge straps for the upper door in interlocking engagement therewith, and

Fig. 5 is a section on line 5—5 of Fig. 4.

Similar reference characters refer to similar parts throughout the several views in the drawings.

Referring to the drawings, 1 represents a wooden washing machine cylinder of any usual or suitable construction having in the periphery at least one door opening provided with a large or main upper door 2 and a narrow lower door

3. At the lower edge of the door opening is a wooden sill 4. In order that the door 3 shall be rigid, it preferably takes the form of a heavy stiff metal trough into each end of which is fitted a metal block 5 secured in place by bolts

6 or otherwise. The movable hinge leaves 7 for the lower door 3 are preferably cast integral with the blocks 5. The stationary hinge leaves for the lower door are Z-shaped; each consisting of a central section 8 adapted to rest on a depressed seat 9 at the front and below the top of the sill; a lower section or wing 10, adapted to rest against the front face of the sill and against the periphery of the cylinder; and an upper section 11 extending up in contact with the sill to the top thereof. In order to provide room

for the hinge leaf sections 8 and 11, the sill is notched to permit the upright section 11 to lie inwardly of the door when the latter is closed, and the section 8 to underlie the closed door. At the upper end of each stationary hinge leaf for the lower door is a lip 12 that projects inwardly and rests upon the sill. These stationary hinge leaves are secured in place by one or more bolts. In the arrangement shown, there are two bolts for each hinge, a short bolt 13 passing through the lower section and through a cylinder stave 14 adjacent to the sill, and a long bolt 15 that extends through the lower hinge leaf section and through the sill. 5 10 15

In order to hold the upper sections of the stationary hinge leaves firmly in place, in the arrangement shown, there is riveted to the inner or rear face of each of the hinge leaf sections 11 or formed integrally therewith a stiff metal tongue 16 that extends down a considerable distance below the central hinge leaf section 8. Slots cut down into the sill at the inner ends of the seats 9 receive the tongues 16 when the stationary hinge leaves are set in place. These slots are preferably so proportioned that the tongues will fit snugly within them. Each tongue is provided near its lower end with a bolt hole 17 so located that the corresponding bolt 15 passes therethrough. Thus, after a stationary hinge leaf has been placed in position 20 25 and the two bolts have been applied, the upper section of the hinge leaf is tied down to the bolt 15 and is therefore securely anchored to overcome any tendency that it may have to spring away from the sill behind it and thus open a 30 35 crack or crevice.

As is customary in this type of construction, the hinge leaves or straps 18 on the upper or main door are continued past the free end or edge of that door so as to overlap the lower door 40 sill when the upper door is closed. In the present construction, the straps 18 are so placed as to cause them to engage with the outer sides or faces of the upper sections 11 of the stationary hinge leaves for the lower door. The stationary hinge 45 leaf sections 11 and the straps 18 are, furthermore, so proportioned and shaped that they become effectively interlocked when the doors are closed, to prevent relative movements circumferentially or longitudinally of the cylinder. To this 50 end, each strap 18 is provided at its free end, on its under or inner side, with a U-shaped rib or bead 19. In the arrangement shown, this U-shaped rib or bead comprises relatively low ribs 21, 21 at the long edges of the strap 18, and 55

a relatively high connecting cross rib or bead 22 following the lower edge. In the front face of each of the hinge leaf sections 11 is a pocket or depression 20 adapted to receive the ribbed 5 lower end of the corresponding hinge leaf or strap 18. Projecting outwardly from the upper end of the inner or rear wall of the pocket 20 is a ledge 23 whose length is slightly less than the distance between the ribs 21, 21 on the strap. 10 Therefore, when the upper door is swung down, the lower ends of the straps 18 enter the pockets 20, the ribs or beads 21, 21 passing the ends of the ledges 23, and the rib or bead sections 22 underlying the ledges 23. Fig. 5 illustrates the 15 relation between the ledge 23 and the ribs or beads 21 when the upper door is swung down, whereas Fig. 3 shows the manner in which the ledge overlies the rib or bead 22.

The doors are locked in their closed positions, 20 as heretofore, by catches 24 on the lower door engaging with the body of the cylinder. Since the blocks 5 are properly located for the purpose, they are made hollow so as to serve as casings or 25 housings for the movable elements of the catches. The chambers in the blocks 5 open out through the outer ends of the blocks to permit the passage of the sliding bolt elements 25 of the catches. Preferably these catches take into recesses beneath the cylinder bands 26 and suitable removable keeper plates 27 are preferably interposed between the bands and the catches. 30

It is essential that the doors be tightly closed, since otherwise small pieces of wash are likely to escape through or be caught in the gaps formed 35 between loosely held doors, or between such doors and the edges of the door openings. The tightness of the doors depends upon the relation of the catch and its keeper. If the keeper and catch make tight contact when the doors are swung 40 shut and are at the limit of their closing movement, no troublesome gaps can be formed. In order that the doors may be held tightly closed initially and also after wear has taken place, 45 adjustable means is provided for insuring close contact between the catches and their keepers. By reference to Fig. 3, this means will be seen to comprise a hardened steel stud or bolt 28, mounted for longitudinal adjustment in a threaded bolt hole 29 formed in the upper section 11 of the stationary hinge member for the lower door. The position of the said bolt is such that when the upper door is swung closed, its end bead 22 will come in contact with the outer end of the bolt. Initially, the bolt is set with its outer end 50 spaced just far enough from the plane of the inner surface of the catch keeper 27 to prevent movement of the doors. If, after a period of service, the doors begin to show looseness, the bolt may be backed out the small distance necessary to compensate for the wear that has taken 55 place.

Preferably, it should be possible to make such adjustment without removing the stationary hinge strap from the cylinder. This may be accomplished by providing at the outer end of the bolt 28 a pair of small holes 30 adapted to be 5 engaged by any suitable key, whereby the bolt may be turned to a new position from the exterior of the cylinder when the upper and lower doors stand open. A set screw 31 is provided to hold the bolt 28 in any selected position. A seal 10 strip 32 secured to the outer surfaces of the upper door hinge straps 18 and extending therebetween closes the gap between the lower edge of the upper door and the upper edge of the lower door. The latter door ordinarily engages this seal strip 15 and also the lower ends of the hinge straps 18. Thus the upper door is firmly held in place by the lower door when the latter is closed and the catch engaged behind its keeper. 20

As many possible embodiments may be made of the above invention and as many changes might be made in the embodiment above set forth, it is to be understood that all matter hereinbefore set forth or shown in the accompanying drawings is to be interpreted as illustrative and 25 not in a limiting sense.

I claim:

1. Latching means for a door hinged at one edge of a door opening and having a hinge member comprising a leaf secured to the door and extending entirely across the opening, said latching means comprising a first member secured to the door opening in position to be overlapped by the free end of said hinge leaf, a second member hinged upon said first member and adapted to be 30 closed over said free end, latching means for holding said second member in closed position, and adjustable means on said first member adapted to engage the inner surface of said overlapping hinge leaf, whereby said hinge leaf is held tightly 35 between said second member and said adjustable means. 40

2. Latching means for a door hinged at one edge of a door opening and having a hinge member comprising a leaf secured to the door and extending entirely across the opening, said latching means comprising a first member secured to the door opening in position to be overlapped by the free end of said hinge leaf, a second member hinged upon said first member and adapted to be 45 closed over said free end, latching means for holding said second member in closed position, a hardened screw normally held immovable in said first member in position to engage with its 50 outer end the inner surface of said overlapping hinge leaf, and means for changing the position or said screw to compensate for wear. 55

WILLIAM STROBRIDGE. 60
